UNITED STATES PATENT OFFICE.

GUSTAV HERRMANN, OF FORT SMITH, ARKANSAS.

SANDPAPERING-MACHINE.

SPECIFICATION forming part of Letters Patent No. 782,245, dated February 14, 1905.

Application filed September 13, 1904. Serial No. 224,303.

To all whom it may concern:

Be it known that I, GUSTAV HERRMANN, a citizen of the United States, residing at Fort Smith, in the county of Sebastian and State 5 of Arkansas, have invented new and useful Improvements in Sandpapering-Machines, of which the following is a specification.

My invention is an improved sandpapering-machine, and is so constructed and arranged 10 as to facilitate the operation of sandpapering articles of wood either curved or straight.

The object of my invention is to provide a machine for sandpapering round-molded woodwork of all kinds, the special feature 15 being that it will do inside work as well as outside, such as circular or oval frames, &c.

Referring to the accompanying drawings, in which like numbers indicate corresponding parts in each of the several views, Figure 1 20 is a perspective view of my improved sandpapering-machine looking from the southeast corner of the sheet. Fig. 2 is also a perspective view looking from the southwest corner of the sheet. Fig. 3 is a detail vertical sectional view showing how the sandpaper-belt works around the half-circle mold and 25 conforms itself to the shape of said mold.

In said drawings, *a* indicates the sandpaper-belt conforming itself to the shape of the 30 half-circle mold. The piece of work is placed on the table, and by removing the said sandpaper-belt from pulley *b* the work may be moved under the belt. Said belt when replaced on said pulley *b* is ready for work.

35 *c c* represent drive-pulleys for said sand-belt. *d* is a foot-treadle having pivoted to one end the lower end of a rod *d'*, while the upper end, *d''*, of said rod is pivoted to the bearing beam *d³* in the upper end of the bearing *d⁴*, 40 the lower end of which bearing is firmly secured to the framework at *d⁵* of the machine, by means of which pressure can be instantly released at will of the operator, so that the sandpaper-belt can be released to adjust upon 45 the wooden piece as it is put in for operation, the uniformity or bearing of the sandpaper on said wooden piece being regulated by

means of a weight *e*. Placed on each side of my sandpapering-machine and directly opposite each other (see Fig. 3) are two rollers 50 *f f*, which act as guides for said sandpaper-belt while the stock is moved along being sandpapered.

h h represent two pulleys by means of which my machine is driven.

Thus it will be seen that my machine is of 55 simple construction, can be readily and easily operated and adapted to do inside work as well as outside, such as circular or oval frames, &c.

Having described my invention, what I 60 claim as new, and desire to secure by Letters Patent, is—

1. The combination in a sandpapering-machine, having a belt *a*, which conforms itself to the shape of the wooden piece to be operated on, of a pulley *b*, so constructed as to allow the sand-belt to be removed therefrom, while placing said sand-belt over the work to be operated on; two sand-belt drive-pulleys 65 *c c*; a foot-treadle *d*, by which pressure can 70 be released at will on work being sandpapered, the pressure on said work being regulated by a weight *e*; two rollers *f f*, placed on each side of opening of machine to act as guides for the sand-belt, and two pulleys *h h*, by 75 means of which the machine is driven, substantially as shown and described and for the purposes set forth.

2. A sandpapering-machine, consisting of a covered frame; two sand-belt drive-pulleys 80 *c*, journaled in the lower part of said frame; two drive-pulleys *h h*, secured on the same shafts with said pulleys last mentioned; a bearing *d⁴*, secured to said framework; a bearing-beam *d³*, pivoted in the upper end of 85 said bearing; a sandpaper-belt pulley *b*, journaled in one end of said bearing-beam immediately over said sandpaper-belt pulleys; a sandpaper-belt, working over the pulley *b*, the pulleys *c c*, and over the material to be 90 sandpapered; a weight *e*, hanging on one end of the bearing-beam *d³*, and adapted to be moved backward and forward, thereby regulating the tension of the said belt; a foot-

treadle d , pivoted to the lower part of the said frame, and a rod having its lower end d' , pivoted to one end of said treadle, and its upper end to said bearing-beam d^3 , said treadle 5 adapted to relieve the tension on said sand-belt, substantially as shown and described and for the purposes set forth.

In testimony whereof I affix my signature in presence of two subscribing witnesses.

GUSTAV HERRMANN.
